UNITED STATES PATENT OFFICE.

CLARENCE WILLOUGHBY WAGNER, OF BRANTFORD, ONTARIO, CANADA.

TABLE BASEBALL.

1,406,308.

Specification of Letters Patent. Patented Feb. 14, 1922.

Application filed January 22, 1921. Serial No. 439,165.

To all whom it may concern:

Be it known that I, CLARENCE WILLOUGHBY WAGNER, a citizen of the United States, of the city of Brantford, in the county of 5 Brant, in the Province of Ontario, Canada, have invented certain new and useful Improvements in Table Baseball, of which the following is a specification.

My invention relates to improvements in 10 table baseball and the object of the invention is to devise a game in which a base-ball diamond and bases may be utilized to make the scores and it consists essentially of a 15 table top or platform carried on a suitable structure and provided with upwardly extending walls located on the central portion thereof and arranged in diamond shape and walls forming paths leading to each base of the diamond, a receiving hopper into which 20 the balls are thrown so situated that the balls discharged therefrom may enter and follow any of the paths leading to a base, and a tiltable discharge receptacle located above the aforesaid hopper into which the 25 ball is manually thrown and which is tilted by the player immediately it receives the ball so as to discharge it in an uncertain direction into the hopper as hereinafter more particularly described by the following 30 specification.

Fig. 1 represents a plan view of my apparatus by which the game I designate as table base-ball is played.

Fig. 2 is a longitudinal section through 35 Fig. 1.

Fig. 3 is a perspective detail of a portion 40 of the table top showing the walls forming the diamond and the walls forming the paths leading to the base portions around the diamond.

Fig. 4 is an enlarged sectional detail of one of the pockets or cups located at each base and by which the ball is received.

In the drawings like characters of reference 45 indicate the corresponding parts in each figure.

1 indicates a table the top 2 of which is provided with a surrounding wall 3. In the center of the table top slightly towards the 50 end from which the game is played is located a base-ball diamond formed by flange-like walls 4, 5, 6 and 7 arranged in diamond shape. At the points of the diamond are located orifices formed in the table top and 55 which are designated 4^x, 5^x, 6^x and 7^x. Towards the opposite end of the table is lo-

cated a ball receiving hopper 8 which rests upon the walls 3 of the table top. The sides of the hopper are preferably inclined inward.

9 is an inclined runway extending forward from the rear end of the hopper and 10 is an inclined runway extending from the forward end of the hopper and overlapping the runway 9 and spaced apart therefrom at 60 its end so as to form an opening 11 through which the balls by which the game is played pass to be discharged through an opening 12 located between the forward end of the runway 9 and the forward wall of the hopper 8. 70

13, 14, 15, 16, 17 and 18 are flange walls which extend upward from the face of the table and longitudinally thereof the rear ends of the walls terminating slightly beyond the opening 12 of the hopper 8. The 75 walls 13, 14, 15, 16, 17 and 18 diverge slightly outward towards their opposite end. The walls 13 and 17 terminate at a point approximately opposite the center of the base-ball diamond formed by the walls 4, 5, 80 6 and 7. The wall 18 is provided with an inwardly inclined extension 19 which terminates opposite the forward end of the diamond and in front of the orifice 6^x. The wall 17 is provided with an inwardly inclined 85 wall extension 20 which converges towards the wall 19 and terminates at the opposite side of the orifice 6^x.

The ends of the walls 19 and 20 are connected together by a cross piece or plate 21 90 on which is indicated by the numeral "2" and the letter "B" the second base position. Between the wall extension 20 and the wall 7 of the diamond in front of the orifice 7^x extends an indicating piece or plate 22 on 95 which is inscribed the numeral "3" and the letter "B" indicating the third base. The wall 14 extends to the outside of the orifice 5^x, its forward end being connected by an indicating piece or plate 23 to the wall 6 of 100 the diamond, such indicating plate having inscribed thereon the numeral "1" and the letter "B" indicating the first base. The walls 4 and 5 of the diamond are slightly spaced apart at their rear ends, the spaced 105 apart ends being connected together by an indicating piece or plate 24 having the letters "HB" inscribed thereon indicating home base. The walls 15 and 16 extend rearwardly from the indicating piece 24 and at 110 each side of the orifice 4^x.

It will thus be seen that a path 25 is

formed between the walls 15 and 16 directing the ball to the home base orifice 4^x. A path 26 is formed between the walls 15 and 14 leading to the first base orifice 5^x. A path 5 27 is formed between the walls 14 and 13 and wall extension 19 and diamond wall 6 leading to the second base orifice 6^x. A path 28 is formed between the wall 16 and the wall 17 leading to the third base orifice 10 7^x and a path 29 formed between the walls 17 and 18 and a path 30 formed between the wall 18 and outer wall 3 of the table top which lead forwardly in front of the baseball diamond and to what is known as a 15 foul line.

Between the wall 13 and outer wall 3 of the table top is formed a path 31 also leading to the foul line. The foul line may be indicated by walls 32 and 33 which serve to 20 stop the ball passing along either of the paths 29, 30 or 31 so that if a ball passes along any of these paths it represents a foul.

34 are standards which extend up from the 25 hopper 8 and between which is tiltably mounted a small receptacle 35 which may be in the form of a basket. 36 is a string or cord connected with the rearward portion of the basket or receptacle 35, such string or cord extending forwardly, the player standing at the position "A," (Fig. 2).

In playing the game each player selects a ball which is identified by a name or a number or in some other suitable way and as 35 each player plays he picks up the free end of the string cord 36 in one hand and throws his ball into the receptacle 35, and as it enters such receptacle he pulls the cord 36 so that the receptacle 35 is tilted and the ball 40 ejected therefrom in an uncertain direction into the hopper 8 passing through the orifices 11 and 12 onto the table top so as to enter one of the paths 25 to 31 following such path either to one of the base orifices or into 45 the foul position.

If the ball enters the path 25 and orifice 4^x the player makes a home run at the first throw. If, however, the ball enters the path 50 26 and orifice 5^x he makes the first base. The next throw he may make the second or the third base or even a home run, the number of home runs obtained by the player or team winning the game.

In order to visibly indicate the score made 55 by each ball I have provided the following device. 37 is an indicator of the type employed as a floor indicator in a building or room indicator in a dwelling in which the pressing of the bottom closes the circuit through the indicator so as to indicate the corresponding room or floor number.

Beneath each orifice 4^x, 5^x, 6^x and 7^x are located pockets or cups which are cylindri-

cal in form and which are indicated in Fig. 4 and designated by the numeral 38. The 65 pocket or cup is provided with a freely movable bottom 39 of insulating material which rests upon a finger contact 40 secured to the wall of the pocket or cup at one side thereof. The free end of the finger contact 70 40 contacts with the stationary contact 41 also carried by the pocket or cup 38. The finger contact 40 and stationary contact 41 are suitably insulated from the cup and from these contacts circuit wires 42 and 43 lead 75 to the operating mechanism of the indicator 37 such circuit wires being energized by any suitable means (not shown).

It will thus be seen that when a ball is played and drops into one of the pockets 4^x, 5^x, 6^x 80 or 7^x the movable bottom 39 of such pocket is depressed forcing the free end of the finger 85 40 into engagement with the stationary contact 41 thereby closing the circuit formed by the wires 42 and 43 and operating the indicating mechanism to visibly indicate the pocket which the ball has entered.

From this description it will be seen that I have devised a very simple apparatus for playing table base-ball in which a certain 90 amount of skill may be exercised in order to so throw the ball that it would be directed in a certain course and thereby provide a game in which a great amount of competition is provided between the players to 95 make the game of particular interest.

What I claim as my invention is,

1. In a game of table base-ball, a table having a top provided with a surrounding edge barrier, a hopper supported above the table top, flanged walls extending upwardly from the table top in diamond form, a pocket located beneath an orifice formed in the table top at each point of the diamond, flanged walls extending from each of the aforesaid orifices to beneath the hopper to form intervening paths, and a path leading to each orifice.

2. In a game of table base-ball, a table, walls extending upwardly from the surface 110 of the table and arranged in diamond form the points of the diamond representing the base positions, and a path leading longitudinally from each of the base positions towards the opposite end of the table and terminating at a point intermediately of its length.

3. In a game of table base-ball, a table, walls extending upwardly from the upper surface of the table and arranged in diamond form the points of the diamond representing the base positions, and a path leading 120 from each of the base positions longitudinally towards the opposite end of the table.
